UNITED STATES PATENT OFFICE.

LADURA ALEXANDER BROWN, OF UNIONTOWN, PENNSYLVANIA.

ATTACHMENT PLUG.

Application filed March 10, 1926. Serial No. 93,738.

This invention relates to attachment plugs for making electrical connections and more particularly to attachment plugs having a removable enclosed fuse in each side of the circuit, and a removable cap carrying contacts which cooperate with clips in the body of the plug.

One object of the present invention is to provide a plug so constructed that it must be removed from its socket before access can be had to the fuses, thereby eliminating any possibility of the workman being shocked by coming into contact with a charged portion of the plug when changing the fuses.

Another object is to provide an attachment plug having the novel design, construction and combination of parts herein-after described in detail and illustrated in the accompanying drawings.

In the drawings:

Figure 1 is a sectional view through a plug constructed in accordance with this invention.

Figures 2 and 3 are side elevations of the body of the plug taken at right angles to each other.

Figure 4 is a plan view of the bottom or cap end of the body.

Referring more particularly to the drawings, the numeral 2 designates the body portion of the plug as a whole, which is preferably formed from molded insulation, such as bakelite or porcelain. The body has a cylindrical neck 4 provided with a screw-threaded metallic sleeve or shell 5. The sides of the body are recessed to form fuse receiving pockets 6 and 7 divided or separated from each other by a center portion 8 of the body. The body 2 is further cut away at each side of the recesses or pockets 6 and 7 as at 9 to permit grasping of the fuses.

Fuse clips 10 and 11 are secured adjacent the opposite ends of the pockets 6 and fuse clips 12 and 13 are secured adjacent the opposite ends of the pocket 7. A center contact 14 is mounted in the neck end of the body 2 and extends into the chamber 6 and is connected with the fuse clip 10. A conductor 15 extends through the body 2 and is connected to the sleeve or shell 5 and fuse

clip 12 in the pocket 7. The lower fuse clips 11 and 13, respectively, are connected to line terminals 16 and 17, respectively, which terminate in spring contact ends 18 and 19, respectively, in recesses 20 and 21, respectively. An attachment cap 22 is provided with prongs 23 and 24 adapted to project into the recesses 20 and 21 and engage with the contact ends 18 and 19 of the line terminals.

Fuses 25 and 26 are adapted to be secured in the clips 10 and 11 and 12 and 13, respectively.

A cylindrical shell 27 of insulating material is mounted around the body portion and is screw-threaded on the body as at 28 at the lower end and bears against a shoulder 29 formed on the body 2. The opposite or upper end of the shell 27 terminates at 70 the inner end of the neck portion 4 of the body and is adapted to be in close relation to the receiving socket when the plug is screwed into operative position, so that the plug must be removed from the receiving 75 socket or receptacle before the shell 27 can be removed from the plug body to permit access to the fuses. This relatively simple mounting of the shell 27 is a highly important detail since it positively prevents 80 the workman gaining access to the fuses while the plug is in electrical connection with the line and thereby eliminates any danger of his becoming shocked by coming into contact with charged portions of the 85 plug when changing fuses.

While I have shown and described one specific embodiment of my invention it will be understood that I do not wish to be limited thereto since various modifications 90 may be made without departing from the scope of my invention as defined in the appended claim.

I claim:

In combination with a conventional form 95 of screw socket, a fused attachment plug comprising a substantially cylindrical body cut away at opposite sides to form separate fuse pockets for the accommodation of fuses and fuse clips, said body being further cut 100 away at each side of said fuse pockets to form an opening to permit the operator to

readily grasp the fuses when changing said fuses, a screw shell and center contact carried by said body, line terminals having fuse clips connected to one end and having their other ends terminating in spring contact ends, an attachment cap having a flexible conductor and prongs adapted to engage said terminal clips, and a substantially cylindrical insulating shell screw-threaded 10 at one end and bearing against a shoulder

formed on said body, the opposite end of said shell terminating at a point adjacent one end of the screw shell so that said cylindrical shell can only be removed to permit access to said fuses after the attachment plug is unscrewed from said socket. 15

In testimony whereof, I have hereunto signed my name.

LADURA ALEXANDER BROWN.
